DESIGN FOR A CANDLESTICK BASE OR ARTICLE OF ANALOGOUS NATURE

Ernest T. Beck, Gasthof, Germania, Bregenz,
Austria, assignor to International Silver Com-
pany, Meriden, Conn., a corporation of New
Jersey

Application August 26, 1933. Serial No. 49,110

Term of patent 7 years

To all whom it may concern:

Be it known that I, ERNEST T. BECK, a citizen of the United States residing at Gasthof, Germania, Bregenz, Austria, have invented a new, original, and ornamental Design for Candlestick Base or Article of Analogous Nature, of which the following is a specification, reference being had to the accompanying drawing, forming a part thereof.

The figure is a perspective view of a candlestick base, showing my new design.

The design is intended to be used on bases for candlesticks, candelabra, compotes and similar articles.

I claim:

The ornamental design for a candlestick base or article of analogous nature, substantially as shown and described.

ERNEST T. BECK.
